UNITED STATES PATENT OFFICE.

WILLIAM F. BURR, OF AGAWAM, MASSACHUSETTS, ASSIGNOR OF ONE-HALF
TO OSCAR L. KING, OF SAME PLACE.

SWITCHING DEVICE FOR RAILWAYS.

SPECIFICATION forming part of Letters Patent No. 636,197, dated October 31, 1899.

(Application filed June 12, 1899. Serial No. 720,138. (No model.)

To all whom it may concern:

Be it known that I, WILLIAM F. BURR, a citizen of the United States of America, and a resident of Agawam, in the county of Hampden 5 and State of Massachusetts, have invented certain new and useful Improvements in Switching Devices for Railways, of which the following is a full, clear, and exact description.

The object of this invention is to provide a 10 novel switching device for street-railways which is of simple construction and automatic in action to switch the car to the siding or branch or to insure the running of the car on the main or straight track, accordingly as 15 the car reaches the switch running slowly or at a considerable speed.

The invention consists in the combination and arrangement of parts and the construction of certain of the parts, all substantially 20 as hereinafter described, and set forth in the claims.

Reference is to be had to the accompanying drawings, in which—

Figure 1 is a perspective view of a portion 25 of a street-railway comprising the junction of the main trackway and the siding and showing the provision thereat of the novel switching device. Fig. 2 is a perspective view, on a larger scale, of the switching device, a portion 30 of the inclosing casing therefor being in vertical section.

Similar characters of reference indicate corresponding parts in both views.

In the drawings, A A represent the main 35 car-track rails, and B B the rails of the branch or siding, tread portions of these rails being comprised as portions of the frogs C C², as usual. The plate or frog comprising the tread portion a of the one branch rail has in 40 its top the aperture b, located within which is the roller D, the peripheral portion of which normally protrudes upwardly above the said tread portion a. This roller is spring-supported and yields downwardly against the 45 compression of the comparatively stiff spring G under the weight of the car when directly upon said roller.

As shown, below the aperture b in the frog or plate C is a standard d, rising above a 50 suitable base e, which may be supported on the cross-ties of the railway below the level

of the trackway or pavement. Said standard has its upper portion recessed, as indicated at f, surrounding which recessed part is the yoke or frame g, which constitutes the journal-support for the axle or arbor h of the said roller D, said journal-support being vertically movable relatively to the upright d, and the spring G aforementioned has its upper end in bearing against the under side of said 60 journal-support G, while its lower end has bearing on the base e of the upright. i represents a casing or housing to inclose the said upright spring-journal-bearing support g and the lower portion of the roller, excluding dirt and moisture from said parts. To the rearward of the location of the roller D is a smaller roller j, the axis of which is parallel with that of the roller D, and this roller has the peripheral portion thereof exposed 70 above the tread-surface of the frog or plate C.

As shown, the tread portion a has the roll-seat m therein, the same being in the form of a socket the walls of which extend around to embrace more than half the circumference 75 of the said roll j, retaining the latter against displacement, leaving it, however, free to rotate.

As the car approaches the branch and the driver or motorman desires to proceed along 80 the branch instead of along the straight track he slackens the speed of the car to a very slow rate, and the foremost car-wheel (indicated in Fig. 2 by the dotted lines x) coming to rolling bearing against both of the rollers D j ceases 85 to have tractional action on the tread of the rail, but turns idly on said rollers; but the progressive movement of the car in some degree which is given thereto insures that the car in its forward motion will be swung, the 90 wheel on said rollers being the center of swinging motion, and the opposite car-wheel will take the track-rail of the siding, and then the continued propulsive movement of the car will insure that the forward car-wheel 95 which is at the side of the switch will cause the larger roller D to be bodily depressed against its spring, the car proceeding along the branch therebeyond. On the other hand, should the motorman wish to have the car 100 proceed along the straight track instead of taking the siding he will approach and pass

the switch at a comparatively rapid rate of speed, thereby giving the switching device no opportunity to roll under the car-wheel, which will be carried thereover too quickly 5 to permit such action.

Having thus described my invention, what I claim, and desire to secure by Letters Patent, is—

1. In a railway-switch, one of the track-rails 10 at the siding adjacent its junction with the main track provided with a roller rotatably mounted and having a portion of its periphery normally protruding above the rail-tread.

2. In a railway-switch, one of the track-rails 15 at the siding adjacent its junction with the main track provided with a roller rotatably mounted, and spring-supported, and having a portion of its periphery normally protruding above the rail-tread.

20 3. In a railway-switch, one of the track-rails at the siding adjacent its junction with the main track provided with two rollers rotatably mounted one in advance of the other and having portions of their periphery protruding 25 above the rail-tread so that both may simultaneously receive bearing thereon of the rim of the car-wheel, for the purpose set forth.

4. In a railway-switch, one of the track-rails 30 at the siding adjacent its junction with the main track provided with a roller rotatably mounted and at a short distance therebeyond and with another roller, and spring-supported, and having a portion of its periphery normally protruding above the rail-tread.

35 5. In a railway-switch, one of the track-rails at the siding adjacent its junction with the main track provided with an aperture, a roller having its upper peripheral portion 40 normally protruding above the top of the rail through said aperture, a journal-support for said roller, located below the apertured por-

tion of the rail, and a supporting-spring for said journal-support.

6. In a railway-switch, one of the track-rails 45 at the siding adjacent its junction with the main track, provided with an aperture, a roller having its upper peripheral portion protruding above the top of the rail through said aperture, a journal-support for said roller, 50 located below the apertured portion of the rail, a supporting-spring for said journal-support, and a casing or housing inclosing the spring.

7. In a railway-switch, one of the track-rails 55 or portions comprising the rail-tread at the siding adjacent its junction with the main track provided with the aperture *b* and the upright *d* thereunder having the upwardly-opening recess *f* in its upper portion, the yoke 60 or journal supporting frame *g* encircling the upright and having the roller *D* rotatably mounted therein with its upper peripheral portion protruding above the rail-tread, the spring *G* supporting the yoke, and the inclos- 65 ing casing *i*, substantially as described.

8. In a railway-switch, the plate or frog 70 comprising the tread portion *a* which is a continuation of one of the branch tracks of the railway, constructed with the aperture *b* and the socket *m*, the roller *j* rotatable in said socket *m*, and having a portion of its periphery protruding above the top of the plate, the upright *d* mounted below the aperture *b*, the yoke or frame *g*, the roller *D* journaled in 75 said yoke, and having an upper edge portion thereof normally protruding above the tread of the rail, the spring *G* and the inclosing housing or casing *i*, all substantially as described.
